UNITED STATES PATENT OFFICE.

EARL EMERSON KENNEDY, OF NEEPAWA, MANITOBA, CANADA.

TYPE-WRITER.

1,143,404.

Specification of Letters Patent. Patented June 15, 1915.

Application filed August 30, 1913. Serial No. 727,513.

To all whom it may concern:

Be it known that I, EARL EMERSON KENNEDY, of the town of Neepawa, in the Province of Manitoba, Canada, have invented 5 certain new and useful Improvements in Type-Writers, of which the following is the specification.

The invention relates to improvements in typewriters and one of the objects of the 10 invention is to provide a key controlled means for automatically returning the carriage of the typewriter and at the same time automatically rotating the platen to space the lines.

15 A further object of the invention is to provide a key controlled means whereby the operator can cause the carriage to return any selected distance in a line and at the same time cause the platen to rotate.

20 A still further object is to provide a key controlled means whereby the operator can rotate the platen without returning the carriage.

With the above and other objects in view 25 which will become more apparent as the description proceeds, the invention consists essentially in the arrangement and construction of parts hereinafter more particularly described and later pointed out in the appended claims.

Figure 1 represents a rear view of a typewriter supplied with my invention. Fig. 2 represents an end view of the same. Fig. 3 represents a plan view of the base of the 35 machine and controlling keys, the upper part of the frame being entirely broken away. Fig. 4 is an enlarged detailed side view of the contacting tips and adjoining parts, certain of the adjoining portions of the machine being shown in vertical section. Fig. 5 represents an enlarged detailed vertical cross sectional view through the lower contact tip. Fig. 6 represents an enlarged detailed vertical sectional view through the 40 key bar receiving head. Fig. 7 represents an enlarged detailed perspective view of the key bar suspending bracket. Fig. 8 represents a back view of the lower contact tip suspending rod, the notched bar and adjoining parts, members of which appear in

vertical section. Fig. 9 represents a front view of the upper end of the locking rod, a portion of the main bracket carrying the same and a portion of the adjoining notched cross rod. Fig. 10 represents an enlarged 55 detailed vertical sectional view of the central portion of the lower contact tip suspending rod. Fig. 11 represents an enlarged detailed side view of the lower end of the locking rod and adjoining key bar. Fig. 12 60 represents an enlarged detailed side view of the stop selecting lever and adjoining parts, in section. Fig. 13 represents an enlarged detailed perspective view of the line spacer. Fig. 14 represents an enlarged plan view of 65 a portion of the main bracket and the releasing bar carried thereby. Fig. 15 represents an enlarged detailed perspective view of the lever of the line spacer. Fig. 16 is a face view of the arm 66.

70 In the drawings, like characters of reference indicate corresponding parts in each figure.

1 represents the ordinary typewriter frame presenting the usual corner posts 2, type 75 keys 3, tabulator 4 and ribbon holder 5.

6 represents the usual carriage of which 6' and 6² are the end plates. The rear side of the carriage is swung in the usual way from the carriage rod 7 which is carried by 80 end supports 7' and 7² permanently secured to the frame endwardly and it is mounted upon a roller 8 operating on a rod 9 also carried by the frame.

10 represents the platen mounted on end 85 spindles 11 and 12 carried in suitable bearings presented by the end plates of the carriage. The spindles are both provided with knobs 13 which allow the platen to be readily turned. The mounting of the carriage other than that described is not herein 90 enlarged upon, as it is well known. It is however, for the purposes of this description, to be understood that the carriage can be moved endwise in respect to the frame, 95 sliding on the rod 7 and riding on the rod 9.

14 represents the usual paper guide mounted on the carriage and designed to feed the paper beneath the platen.

15 represents the shift rod located at the 100

back of the carriage and at present used for raising or lowering the carriage when necessary.

11^x is a ratchet wheel fixed on the spindle 5 11 and coöperating with a part later to be described, to rotate the platen one, two or three spaces as the case may be.

The above parts with the exception of the ratchet wheel 11^x form no part of my invention 10 and are not described in detail as they are well understood, being found on various forms of typewriters now on the market. As a matter of reference I may say that the above parts as shown in the drawings appear 15 in the present Underwood typewriter.

16 and 16' are a pair of hangers secured to the carriage, which hangers move therewith and have their extending lower ends connected by a cross bar 16^z, the bar being 20 provided with a space scale 17.

18 is a horizontally disposed rod carried 25 permanently by the extremities of the hangers. The rear side of this rod or that farthest from the frame is formed with a more or less right angled groove 18' running lengthwise of the rod. A series of similar equal spaced teeth 19 extend into the groove, the teeth being V-shaped in vertical cross section and having the apex of the 30 V centered in the angle of the groove. It will here be noticed that the scale has a series of equal spaced marks thereon, which marks correspond in number to the number of spaces which the carriage travels when going 35 from one end of the machine to the other. There is a tooth 19 for every mark, less one, on the scale. The rod is also provided on the inner side or that nearest the frame with a second L-shaped groove 20 which runs lengthwise thereof. Similar 40 equal spaced teeth 21 project into this latter groove, the number of teeth in this instance being the same as the number of teeth on the rear side of the bar. The teeth 21 form a 45 rack on the rod and I wish it to be understood that hereinafter when I refer to the rack I mean the teeth on the inner side of this rod. The purpose of these teeth will be later apparent.

50. 22 is a stop selecting lever carried by a sleeve 22' rotatably mounted on the rod. The sleeve carries an inwardly projecting V-shaped dog 23 designed to enter the spaces between the teeth 19 when the said lever is 55 swung downwardly and to clear from between the teeth and enter the upper portion of the groove when said lever is swung upwardly.

22^z is a stop plate secured to the sleeve and 60 designed to arrest the lever when turned upwardly, said plate engaging with the bar 16^z.

24 is a spring carried by a pin 24' screwed into the sleeve. The spring is arranged to

force the lever downwardly at all times. It 65 will be seen from the above construction that one can shift the lever on the shaft 18 and lock it at any point desired by passing the dog into any selected notch.

25 represents a main bracket located centrally at the back of the machine and permanently secured to the frame. The bracket is constructed to present opposing horizontally disposed top and bottom guides 25' and 25^z, the top guide being supplied with 75 a cross T-shaped groove 26' which receives 70 slidably the releasing bar 26 fitted at one end with an upwardly directed striking tab 26^z.

27, 28 and 29 are three finger keys 80 carried by the bars 30, 32 and 31 respectively, which bars are mounted to swing on a cross rod 33 extending across the machine frame. These keys are located preferably at the ends of the present spacing bar indicated at 34 in 85 Fig. 3 of the drawings. However I do not wish to be limited to any location as they can be put in at any suitable place. The bars 30 and 32 are turned inwardly and connect respectively with further key bars 30' and 90 32' while the key bar 31 is connected to a further key bar 31' pivotally mounted on the rod 33 and located between the bars 30' and 32'. The bars 30, 31 and 32 are pivoted on the rod 33 as are also the forward ends 95 of the bars 30' and 32'. The bars 30', 31' and 32' extend backwardly through a suitable suspending bracket 35 located centrally at the back of the machine frame and have their rearmost ends entering open bottom 100 cross slots 30^z, 31^z and 32^z formed in a head 36 fitted with an extending shank 36' which screw-threads into the lower end of a tubular contact tip suspending rod 37. This rod passes upwardly slidably through a circular opening 37' formed in the guide 25^z and also slidably through a circular opening 37^z appearing in the top guide 25' a short distance above which it terminates. The releasing bar 26 is fitted with a more or 105 less elongated circular opening 26^z which permits the rod to pass through it. This opening is elongated to permit the releasing rod to be shifted endwise slightly for a purpose later explained. The upper end of the 110 rod is supplied with an insulating bushing 38, which receives a contact tip 39 herein-after termed the lower contact tip.

39' is a nut threaded on the contact tip and bearing on the bushing. 120

40 is a wire connected with the contact tip and passing downwardly within the rod from which it is suitably insulated.

41 is a bar having the lower end thereof 125 passing slidably through the head 36 where it is enlarged at 41', the enlargement being received within vertical channels 41^z located in the walls of the cross groove 32^z.

The enlargement 41' is located at all times above the key bar 32'. The upper end of the bar passes first slidably through the bracket 25² and then slidably through receiving slots 42 and 43 located in the guide 25' and the bar 26 respectively, these slots communicating with the openings 37² and 26³ hereinbefore mentioned. The bar is notched to form a catch 44 whereby the bar can be suspended in the upper position, when desired, by the catch engaging with the body of the releasing bar, which bar it will be noticed is held normally in a set position by a flat spring 45 carried by the main bracket 25. The arrangement is such that when the parts are in the position shown in Fig. 8 of the drawings the bar 41 is held in its upper position and cannot release until the tab 26³ is struck in a direction which will carry the slot 43 away from the bar, this motion being permitted by the elongated opening 26³ already referred to. It will here also be noticed that owing to the peculiar connection of the bar 41 with the head, the head is held up at all times with the bar and drops with it, although it is possible for the head to be raised independently of the bar as the enlarged end 41' thereof can slide freely in the grooves 41². 46 is a spiral spring having the lower end thereof permanently secured to the guide 25² and the upper end thereof connected to a hook 46' extending from the rod 37. This spring tends normally to hold the rod in its lower position, and consequently has a constant tendency to hold the head 36, the rod 41 and attachments in their respective lower positions.

47 is a second bracket secured permanently to the bracket 25 and carrying slidably a vertically disposed sleeve 47' in which I have mounted a bushing 47² of insulating material which carries a top contact tip 48. A spiral spring 49 is inserted between the under face of the bracket 47 and the sleeve, which spring tends to hold the sleeve normally in its lowermost position. The upper contact tip 48 is centered directly above the contact tip 39 hereinbefore referred to. 50 is a locking rod having the lower end thereof forked and spanning the bar 31', the forks carrying a roller 50' which operates in a suitable slot 51 formed in the bar. The upper end of the rod is received slidably within an opening 52 located in the guide 25' and the end of said rod is contracted and alined directly with the opening between the teeth 21 of the rack formed on the inner side of the rod 18. In the natural position of the key 29 controlling this rod, the rod is down, that is, away from the rack. 53 represents an electric motor of which 54 is the drive shaft and 55 and 56 are the terminals.

57 represents a number of batteries or other source of electro-motive force, which batteries are connected by a wire 58 with the terminal 55 of the motor and by a wire 59 with the lower contact tip 39, this connection being made through the rod 40, the wire 59 passing to the rod through an insulating ferrule 60 located in the side of the rod 37. The terminal 56 of the motor is connected by a wire 61 with the contact tip 48, the wire being connected to the contact tip by lock-nuts 62 and 63.

64 represents a pulley permanently secured to the drive shaft 54 of the motor.

65 represents a permanent supporting plate secured to and movable with the carriage and mounted on the spindle 11 immediately to the inner side of the ratchet wheel 11^x, it being understood that the ratchet wheel is free to rotate with the spindle, the plate remaining stationary. The plate is supplied with a projecting arm 66 which passes to the side of the ratchet wheel and carries a bell crank 67 pivotally mounted on a pin 67' extending from the face of the arm. One end of the bell crank is connected to a cable 67² which has the opposing end thereof wound around and secured to the pulley 64. The opposite end of the bell crank is jointed and is arranged so that when the said bell crank is turned, the jointed end thereof engages with one of the ratchet teeth of the wheel and upon the continued movement of the bell crank turns the wheel a certain set number of teeth, the joint in the bell crank being provided to permit the same to free from the teeth or drop back after the carriage has been returned.

67³ is a stationary anchoring arm secured by a cross pin 67^x to the pin 67'. The arm is received normally within a slot 67^a provided in the bell crank, as is clearly apparent in Fig. 13 of the drawings.

67^b is a spiral spring having one end secured to the extending end of the arm 67³ and the other end fastened to the jointed end of the bell crank. The spring is supplied to return the bell crank to the initial position after it has been actuated and released by the deenergization of the motor, as later explained. The distance which the bell crank can swing on the pin 67' is controlled by the lever 68 pivotally secured by pivot pins 69 to a swivel 70 rotatably mounted in the arm 66, which arm it will be noticed is notched away to permit the lever to lie normally flush with the upper face thereof. The inner end of the lever is supplied with a pair of stop pins 68' and 68², the pin 68' being arranged to engage with the jointed arm of the bell crank, while the pin 68² is designed to enter suitable holes 71 located in the arm. The outer end of the lever is engaged by a flat spring 72^x which operates on

the lever to hold the inner end thereof with the pin 68² in one or other of the holes 71 according to the adjustment made. The holes 71 are spaced so that the bell crank 5 can turn the ratchet wheel one, two or three teeth as the case may be, depending on whether the pin 68² is in the first, second or third opening 71. The ratchet wheel in turning carries with it the platen so that I 10 am enabled by this construction to turn the platen to cause single, double or triple spacing in writing. For convenience in operating, the arm or lever can be supplied with suitable means to indicate whether the lever 15 is set at the single, double or triple space position.

72 is a grooved collar fixed on the spindle 11 between the knob and the face of the ratchet wheel.

20 73 is a spring bar having the lower end thereof entirely spanning the collar and received within the groove and the upper end thereof passing through a suitable slot 73' located in an overhanging arm 65' carried 25 by the plate 65. The upper end of the spring 73 is forked and bears against a cross pin 74 carried by a locking lever 75 suitably mounted on the arm 65'.

76 is a ball normally engaging with the 30 teeth of the ratchet wheel and carried by a more or less hemispherical socket 77 permanently secured to the body of the spring bar 73. When the lever 75 is in the upright position the ball is engaged with the teeth 35 of the ratchet wheel but upon one swinging the lever downwardly he withdraws the ball from the teeth as the pins 74 force the spring bar backwardly in the slot 73'. The bar is locked in this position by the lever.

40 In order to better understand my invention I will now describe the manner in which the parts operate. At the outset the operator sets the lever 68 so that the machine will write single, double or triple spacing as 45 he may select, the setting being accomplished by depressing the outer end of said lever and inserting the pin 68² in one or other of the openings 71. He next sets the stop-selecting lever 22 with the dog 23 between any 50 selected pair of teeth 19 on the rod 18, thereby limiting the distance which the carriage travels on the return shift. This locking lever actually controls the margin appearing on the left hand side of the type-writing sheet. The carriage is primarily 55 shifted to the initial position and after the line has been written and the operator wishes to return the carriage he depresses the key 28. This key operates the bars 32 and 32' 60 in a manner such that the notched bar 41 is raised as is also the head 36. As the bar 41 rises it is caught and locked in the upper position by the bar 26 which is forced over by the spring 45 immediately the notch 65 said bar 41 is opposing the slot 43. The

parts are so gaged that when the notched bar is so locked, the contact tip 39 is engaged with the tip 48. Immediately this occurs, the circuit is closed through the motor, with the result that it starts rotating 70 and in so doing draws on the cable 67² which winds on the pulley. During the initial pull of the cable the bell crank is swung against the action of the spring 67^b until it engages with the pin 68' of the lever 68, which motion rotates the platen the selected spacing, owing to the bell crank catching the teeth of the ratchet wheel. After this has occurred, the cable continues winding and as the bell crank cannot turn farther the cable 75 draws and returns the carriage until the lever 22 hits the striking tab 26² of the releasing bar. This shifts the bar back against the spring 45 and releases the notched bar 80 from the bar 26. The notched bar, head and rod 37 immediately drop to the original position, this being facilitated by the action of the spring 46. When the rod drops, the contact through the contact tips is broken and the circuit is opened. Immediately the circuit 85 is broken, the motor is deenergized and the spring 67^b operates to return the bell crank to the initial position. The cable, during this operation, is wound off the pulley 90 64, which, due to the deenergizing of the motor, is free to turn. The operator is then ready to type the next line on his sheet. If it should happen that the operator should desire to turn the platen in any lateral position of the carriage and subsequently return the carriage to any other lateral position short of the initial position, he can do this by depressing and holding depressed the key 27 which operates through the bars 95 30 and 30' to shift the head 36 upwardly and 100 make contact between the contact tips. Immediately the contact is made, the motor will operate, first to turn the platen and then to shift the carriage. Immediately the selected lateral position of the carriage is 105 reached, the key 27 is released and the head immediately withdrawing, owing to the action of the spring 46, immediately breaks the contact between the tips and stops the movement of the carriage. It will be seen 110 in this connection that the head operates free of the notched bar. The enlarged end 41' thereof during this operation simply slides freely in the grooves 41² provided. If the operator wishes at any time during the 115 writing operation to turn the platen, he simply depresses the key 29 which operates through the bars 31 and 31' to raise the locking rod 50 and also the head 36. As the locking rod goes up, the upper end thereof 120 engages with the rack on the inner side of the rod 18 and in so doing prevents the rod and consequently the carriage from moving. Further, the head 36 in shifting makes contact between the contact pieces 39 and 48 125 130

with the result that the platen is turned by the cable drawing on the bell crank. Immediately the key in question is released, the head returns and breaks the contact and the locking rod passes away from the rack. It is here explained that it is necessary to have the locking rod lock the carriage before the circuit is closed through the contact tips.

What I claim as my invention is;

1. In a typewriter the combination with the machine frame, a carriage mounted on the frame and laterally movable and having a predetermined initial position and a platen rotatably mounted in the carriage, of a motor adjoining the machine, a main bracket secured to the machine and providing an upper and a lower guide, a second bracket extending from the main bracket, a contact tip carried by the second bracket, a spring-pressed rod slidably mounted in the guides, a contact tip carried by the upper end of the rod but insulated therefrom, said contact tip being alined with the former tip, a head located at the lower end of the rod, a pivoted key bar slidably engaging with the head, a key for actuating the bar and shifting the rod to engage the contact tips, means for automatically locking the rod in the raised position with the contact tips engaged, a suitable electric circuit containing the motor and the contact tips, said circuit being closed when the tips are engaged,

means actuated by the motor in rotating to primarily rotate the platen and subsequently return the carriage to the initial position, as and for the purpose specified.

2. In a typewriter the combination with the machine frame, a carriage mounted on the frame and laterally movable, a platen rotatably mounted in the carriage and a ratchet wheel carried by and rotatable with the platen, of an electrical motor, a pair of normally disengaged contact tips connected in a suitable electric circuit with the motor, means for engaging the tips to close the circuit and rotate the motor, a pivotally mounted spring-controlled bell crank carried by the carriage and adjoining the ratchet wheel, said bell crank having a jointed arm engageable with the ratchet wheel, means limiting the turning movement of the bell crank in one direction, a pulley rotatable with the motor, a cable connecting the bell crank with the pulley and winding on the pulley and means for locking the carriage against movement simultaneously with the closing of the circuit, as and for the purpose specified.

Signed at Neepawa this 11th day of July 1913.

EARL EMERSON KENNEDY.

In the presence of—

E. G. SIRETT,

W. T. M. ROBERTSON.
